UNITED STATES PATENT OFFICE

DAVID M. HASBROUCK, OF JERSEY CITY, NEW JERSEY, ASSIGNOR TO AIR REDUCTION COMPANY, INCORPORATED, OF NEW YORK, N. Y., A CORPORATION OF NEW YORK

DESIGN FOR A WELDING TORCH BODY OR HANDLE

Application filed March 30, 1933. Serial No. 47,634. Term of patent 14 years.

To all whom it may concern:

Be it known that I, DAVID M. HASBROUCK, a citizen of the United States, residing at Jersey City, in the county of Hudson and State of New Jersey, have invented a new, original, and ornamental Design for a Welding Torch Body or Handle, of which the following is a specification, reference being had to the accompanying drawing, forming part thereof.

In the said drawing:

Fig. 1 is a side elevation of a welding torch body or handle, showing my new design; and Fig. 2 is a rear end elevation.

I claim:

The ornamental design for a welding torch body or handle, substantially as shown.

DAVID M. HASBROUCK.
